UNITED STATES PATENT OFFICE

2,265,537

SEPARATOR

Dickinson A. McNeil, Jr., Maywood, Ill.

Application April 27, 1940, Serial No. 331,956

16 Claims. (Cl. 209—479)

My invention relates to a separator and has particular reference to an apparatus adapted for use in separating various kinds of impurities from granular material which are heavier in weight than the material itself, and in which both centrifugal force and the force of gravity are used in such manner that material is stratified so that the heavier particles may be removed from the lighter.

Another and further object of my invention is the provision of an apparatus in which free foreign particles, such as clay, slate, rock and other substances, may be easily and quickly removed from coal, sand, gravel, grain or other products similar in character, in which the impurities to be removed are heavier in weight than the material from which the impurities are to be separated.

Another and further object is the provision of apparatus wherein granular material, such as coal, coke, gravel and similar material may be passed through the machine and in a continuous operation the heavier particles separated from the mass of material and removed therefrom, and at the same time dust, dirt and the like of fine particles are removed in a large measure from the material, passing out with the rejected or heavier weight material.

Another and further object of my invention is the provision of apparatus in which grain, such as corn, wheat or the like, may be cleaned and foreign substances removed therefrom, such as sticks, and foreign particles lighter than the grain, in which case the operation of the apparatus is the reverse for use with coal, coke and the like, as the grain being the heavier is stratified out of the material and passes out of the separator at the bottom thereof instead of through the opening in the central dam as is the case of coal, coke, gravel or the like.

Another and further object of my invention is the provision of a separator comprising a circular tub which is oscillated horizontally preferably through an arc of 120°, with means for supplying a constant stream of material to the tub, the tub having a movable bottom which normally is spaced slightly below the lower edge of the tub to allow for the constant escape of the very fine particles of material from the tub, and which can be further lowered away from the lower edge of the tub thus allowing the foreign or "reject" material to escape from the tub where it has collected on the movable bottom, and thereby removed from the material after it has been stratified in the tub, or if the reverse operation is used, the accept material passes out over the

bottom and the lighter or reject material through a central opening in the dam.

These and other objects of my invention will be more fully and better understood by reference to the accompanying drawings, and in which—

Figure 1 is a side elevational view of apparatus embodying my invention;

Figure 2 is a top plan view of the apparatus shown in Figure 1;

Figure 3 is a vertical cross-sectional view on line 3—3 of Figure 1;

Figure 4 is a vertical view, partially in elevation and partially in section, showing the separator and mounting therefor;

Figure 5 is a transverse sectional view on line 5—5 of Figure 3;

Figure 6 is a detailed sectional view showing the means employed for suspending the valve plate; and

Figure 7 is a detailed perspective view of the valve plate supporting means.

Referring now specifically to the drawings, and in which like reference characters refer to like parts throughout, longitudinal bottom sills 10 and 11 are shown to which a plurality of spaced vertical posts 12, 12 are secured at their lower ends. A longitudinally extending channel member or top sill 13 is provided at the upper ends of the posts 12 at one side of the frame, while at the opposite side a longitudinally extending angle member 14 is provided. The posts are connected transversely by appropriate angles 15, 15. The structure just described constitutes the frame upon which the various moving parts of the apparatus are mounted.

Secured at their ends to certain of the posts 12, 12 and extending longitudinally of the frame is a pair of sills 16, 16 preferably of channel construction, with other sills 17, 17 extending transversely of the frame and secured at their ends

40 to the longitudinally extending sills 16, 16 in any approved manner, the sills 16, 16 and 17, 17 forming the supports for the mountings for the separating apparatus. A circular track member 18 is secured to the sills 16, 16 and 17, 17 and is held in position by bolts 19, 19 which extend through the sills 16 and 17, respectively, and has openings 18a, 18a therein for access to bottom suspension means for adjustment purposes as hereinafter described.

45 A tub 20, circular in form, is provided having bolts 21, 21 passing through its wall, on the outer ends of which rollers 22, 22 are mounted, having an extension rim 23 formed at the outer portions thereof so the tub 20 is held in position on the track 18. The upper edge of the member 18

50

therefore forms a track upon which the rollers 22 travel and which, in turn, support the tub 20 upon the circular member 18 and allow for rotary movement of the tub 20. A cover plate 24 is secured to the upper side of the tub 20 in any approved manner, having an opening 25 therein. A ring gear 26, mounted upon the cover plate 24, forms the means by which the tub 20 is rotated by suitable power means hereinafter described.

A dam 27 is mounted centrally of the tub 20 upon the lower ends of arms 28, 28 which extend through the ring gear 26 and opening 25 in the cover 24, with an opening 29 therein through which the accepted material is discharged during the operation of the device. The accepted material passes through the opening 29 into the hollow dam 27 and is discharged downward and drops into a receptacle 30 supported in any suitable manner as by angles 31, 31 secured to the bottoms of the vertical posts 12. A valve plate 32 is provided which forms a substantial closure member for the bottom of the tub 20, the valve plate 32 having an opening at the central portion thereof with a tubular portion 33 connected thereto and extending downward therefrom, and having a plate 34 having a central opening therein through which the tubular portion 33 extends, which is secured to a collar 34a integrally formed with the plate 34, which is in spaced relation to the valve plate 32 for purposes hereinafter described. The lower end of the dam 27 extends within the tubular portion 33 and normally operates in telescopic relation therewith.

The plate 32 extends beyond the bottom edge of the tub 20 and has a plurality of eye-bolts 35, 35 mounted therein around its outer edge which extend through guide angles 36 and 37 on the side of the tub 20. A plurality of turnbuckles 38, 38 are mounted in the cover 24 around the outer edge thereof which extends over the edge of the tub 20, with springs 39, 39 being interposed between the eye-bolts 35 and the turnbuckles 38. The springs 39 normally exert their force in an upward direction and may be adjusted by means of the turnbuckles 38 to the proper tension to support the plate 32 and the lading thereon in proper position with respect to the bottom of the tub 20. Nuts 39a are mounted in the eye-bolts 35 by means of which the plate 32 is normally held in fixed spaced relation below the bottom edge of the tub 20, thereby allowing for the constant escape of the fines, such as dust and dirt, during the normal operation of the apparatus. In the separation of grain and the like from lighter substances, the grain passes out of the tub under the lower edge thereof during the reciprocating of the tub, where it is conveyed to the proper receptacle to receive it. Stops are provided on the sides of the tub 20 through which the eye-bolts 35 extend, with some of the nuts 39a below these stops and others above them so the plate 32 is held in proper adjusted spaced relation with the bottom of the tub 20.

The valve plate 32 is also additionally supported by a plurality of arms 40, 40 which are bent inward at their lower ends and have a plurality of rollers 41, 41 mounted thereon which engage against the under side of the valve plate 32 and the upper side of the plate 34. The arms 40, 40 extend upward with their upward ends turned inward and mounted in a ring 42. The ring 42 is pivotally mounted upon a yoke 43, the ends

of which are mounted in short vertical posts 44 and 45 which are welded or otherwise secured to the sill 13. The yoke 43 has a handle portion 46 to which a spring 47 is secured, the upper end 5 of which is secured to an eye-bolt 48 mounted in an angle 49 secured at its ends to a pair of vertical angles 50, 50. The angles 50, 50 are in turn welded or otherwise secured at their lower ends to angle irons 51, 51 which extend transversely of the structure and are secured to the vertical posts 44 and 45 on one side of the frame and to the vertical posts 44a and 45a welded to the angle 14 at their lower ends.

Mounted on the sills 17, 17 are vertical plates 15, 52, 52 which, in turn, have angularly disposed plates 53, 53 secured thereto, with an opening centrally of these plates through which the accepted material passes to the receptacle 30. The lower edges of the plates 53, 53 extend over the 20 receptacles 54, 54, one of which rests upon the edge of the sill 11 and a second sill 55, while the other receptacle rests upon and is supported by the channel member 10. These receptacles are adapted to receive the reject material which is dumped from the tub 20 when the valve plate 32 is lowered during the operation of the apparatus, so that this reject material passes into the receptacles 54, 54 and can be removed from the machine or otherwise disposed of as may be desired.

A hopper 56 is provided which is supported on the machine in any suitable manner, as by vertical angles 57, 57 and has a base portion 57a which is integrally formed with the side walls 35 and is supported upon one of the transverse angles 51 at one of its ends. A belt 58 is mounted upon a roller shaft 59 at one end and a second roller shaft 60 at its opposite end, supported by brackets 61, 61 at one of its ends and by brackets 61a, 61a mounted on angle 51 at its opposite end, the brackets 61, 61 being mounted upon the sill 13 and the angle 14. An inclined discharge chute 62 is provided which is connected to the base portion 57a of the hopper at its upper end, the lower end of which extends into the tub 20 at one side thereof and through which the material adapted to be separated is conveyed into the tub 20. The material may be conveyed into the hopper by a conveyor or the hopper may be placed under a bin having a discharge spout leading therefrom, with the material flowing into the hopper by gravity and conveyed into the tub 20 over the belt 58 as desired.

Mounted upon a pair of longitudinally extending members 63, 63 is a motor 64 having a belt 65 leading therefrom to a pulley 66 mounted upon a shaft 67 suitably mounted in bearings secured to the top sill 13 and the angle 14. A smaller pulley 68 is provided over which a belt 69 operates to a pulley 70 mounted upon a shaft 71 suitably supported in bearings in the top sill 13 and the angle 14. A connecting rod 72 is secured to the disc 70a by means of a bolt 73 and at its inner end is secured to a rack 74 suitably mounted in bearing blocks 75, 75 secured to angles 76, 76 which are appropriately secured to the angles 51, 51 at their outer ends. In turn, the rack 74 is in mesh with a small gear wheel 77 mounted upon a shaft 78 suitably supported in bearings 70 mounted upon the top sill 13, and has a gear wheel 79 on the inner end thereof which is in mesh with the ring gear 26 secured to the cover plate of the tub 20 by means of which the tub 20 is oscillated through the application of power from the electric motor and the train of belts and

pulleys hereinabove described. A small pulley 80 is mounted on the shaft 71 to which a belt 81 is connected leading to a pulley 82 on the roller shaft 59 over which the belt 58 travels, which operates as a feeding mechanism for supplying the material to be separated to the chute 62 where it flows by gravity to the tub 20.

Secured to an angle brace 83 forming part of the supporting frame is a spring contact member 84 preferably of S-shape, having a lead wire 85 leading to any suitable source of electrical supply, such as a battery or the like. A bracket 86 is provided upon which a lamp 87 is mounted, with a lead wire 88 leading therefrom and returning to the source of electric supply, the circuit being established through the contact member 84 and frame of the machine to the lamp 87, so that when the lower plate 34 is in engagement with the contact member 84 the circuit is closed, resulting in the lamp 87 being lighted and signalling the operator that a sufficient quantity of reject material has collected in the tub 20 to force the plate downward slightly away from the bottom of the tub 20 and is ready for the operator to lower the valve plate 32 thereby allowing the reject material to be conducted out of the tub.

In the operation of the device, the material, such as coal, grain, gravel and the like, which it is desired to separate, is placed in the hopper 56 and passes into the tub 20 over the belt 58 and supply chute 62, the tub in the meantime being oscillated through an angle of approximately 120° by means of the rack 74 and power applying connections to the ring gear 26. As the tub is oscillated, the heavier reject pieces of material pass to the bottom and outer side of the tub where they lie upon the plate 32, and, due to the centrifugal force exerted upon these particles, are forced into the corners of the tub, lying partially against the wall of the tub 20 and the bottom plate 32. Through this operation the material is stratified by gravity, and centrifugal force imparted to the material in the tub 20 causes it to collect in the corner of the tub where it builds up against the wall of the tub 20 and on the bottom of the tub. The lighter material is forced toward the center of the tub where it passes out through the opening 29 in the dam 27 and is dropped into the receptacle 30. As the reject material collects in the corner of the tub 20 its weight gradually increases until the plate 32 drops downward a slight distance and the contact is made through the contact 84 to the signal lamp 87. Thereupon the operator grasps the handle 46 and by exerting a downward pull on this handle the valve plate 32 is forced downward away from the bottom of the tub 20, allowing the reject material to be thrown out under the lower edge of the tub and over the outer edge of the plate 32 and onto the plates 33 or against the side plates 52, where it drops to the receptacles 54, 54. The operator thereupon immediately releases the handle 46 and the combined force of the springs 47 exerted upon the yoke 43 and the springs 39 pull the valve plate up into position slightly below the bottom of the tub 20, with angle stops 89, 89 being provided with which the sides of the ring 42 come into contact. The adjustment of the springs is such that a considerable amount of material can be carried in the tub 20 with the valve plate held in close engagement against the bottom of the tub, and only after a considerable amount of material, including heavier foreign matter, has been built up in the bottom of the tub do the springs allow the

valve plate to drop a sufficient distance so that contact is made with the signalling apparatus.

The opening 29 in the dam 27 should be larger than the maximum sizes of material adapted to pass therethrough, so that regardless of the size of these pieces of material they will pass freely through this opening and will not lodge against the sides of the opening, thereby damming up the material and preventing the lighter material from flowing out of the tub 20. Due to the fact that rock, slate, mineral matter and the like, particularly in coal, are considerably heavier than the coal itself, this material quickly passes to the bottom of the tub 20 during the operation thereof. Due to the centrifugal action of the tub the material builds up around the outer edge of the tub and the lighter material moving toward the center of the tub against the dam is discharged through the opening 29. In this manner the heavier particles of material, such as slate and the like, are easily and quickly separated from the lighter materials, such as coal, as it is passed through the machine.

When used for cleaning grain of sticks, lighter material and the like, the operation of the apparatus is the same as for coal, except that the grain, being heavier, escapes under the edge of the tub 20 while the lighter material flows through the opening 29 into the dam 27.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

What is claimed is:

1. A separator comprising, in combination, a frame, a tub mounted for oscillating movement on said frame, power means whereby the said tub is oscillated, means whereby material is supplied to the said tub, a hollow dam centrally mounted of said tub having a discharge opening therein, a movable bottom for said tub, and means whereby the said bottom may be moved away from said tub.

2. A separator comprising, in combination, a frame, a tub mounted for oscillating movement on said frame, power means whereby the said tub is oscillated, means whereby material is supplied to the said tub, a hollow dam centrally mounted of the said tub having a discharge opening therein, a movable bottom for said tub, means whereby the said bottom is normally held in spaced relation with the bottom of the said tub, and manual operable means whereby the said bottom may be moved away from the said tub to allow reject material to pass out of said tub.

3. A separator comprising, in combination, a frame, a tub mounted for oscillating movement on said frame, power means whereby the said tub is oscillated, means whereby material is supplied to the said tub, a hollow dam centrally mounted of the said tub having a discharge opening therein, a movable bottom for said tub, spring support means whereby the said bottom is held in spaced relation with the said tub, and manual operable means whereby the said bottom may be moved out of its normal position away from the said tub.

4. A separator comprising, in combination, a frame, a tub mounted for oscillating movement on said frame, power means whereby the said tub is oscillated, means whereby material is supplied to the said tub, a hollow dam centrally mounted

of the said tub having a discharge opening therein, a movable bottom having a central opening therein within which the hollow dam extends, comprising a plurality of spaced plates, means whereby the said bottom is supported in spaced relation with the bottom of said tub, a plurality of arms extending between the plurality of plates of the said bottom, a yoke to which said arms are connected at their upper ends, and a spring normally tending to support the said bottom secured to the said yoke.

5. A separator comprising, in combination, a frame, an oscillating tub mounted on the said frame, power means whereby the said tub is oscillated, means whereby material is supplied to the said tub, a hollow dam centrally mounted of the said tub having an opening therein through which the accepted material passes, a movable bottom having an opening therein through which the dam extends in the normal closed position of the bottom, adjustable spring support means for the said tub, arms extending under said bottom and in normal engagement therewith, a yoke to which said arms are connected having a handle portion, and a spring normally tending to retain the bottom in closed position.

6. A separator comprising, in combination, a frame, an oscillating tub mounted on the said frame, power means whereby the said tub is oscillated, a cover plate for the said tub, means whereby material is supplied to the said tub, a hollow dam centrally mounted of the said tub having an opening therein through which the accepted material passes, a movable bottom having an opening therein through which the dam extends in the normal closed position of the bottom, adjustable spring support means for the said tub connected to said cover plate, arms extending under said bottom and in normal engagement therewith, a yoke to which said arms are connected having a handle portion, and a spring normally tending to retain the bottom in closed position but spaced from the bottom of the said tub.

7. A separator comprising, in combination, a frame, an oscillating tub mounted on said frame, a cover for said tub extending over the upper edge of the said tub, means whereby material is supplied to said tub, a hollow dam centrally mounted of the said tub having an opening in the wall thereof through which the accepted material passes, a movable bottom into which the dam extends, support assembly for said bottom consisting of units of turn-buckles, eye-bolts and springs connected together, one end of each unit being connected to the cover plate and the other end to the bottom whereby the said bottom is normally suspended in spaced relation with the said tub, and dumping means for the said tub comprising arms extending under one portion of said bottom and secured to a movable yoke at their upper ends, and spring means tending to assist the support assembly in holding the movable bottom in position below the said tub.

8. A separator comprising, in combination, a frame, an oscillating tub mounted on said frame, a cover for said tub extending over the upper edge thereof, means whereby material is supplied to said tub, a hollow dam centrally mounted of the said tub having an opening in the wall thereof through which the accepted material passes, a movable bottom comprising a closure member, a hollow member into which the said dam extends and a plate connected to said hollow member and in spaced relation with the said closure member,

support assembly for said bottom consisting of units of turnbuckles, eye-bolts and springs connected together, one end of each unit being connected to the overhanging edge of the cover plate and the other to the bottom whereby the said bottom is normally held in spaced relation with the said tub, arms extending alongside of the said tub having their lower ends extending between the said closure member and the spaced plate, rollers on said arms, a yoke to which the said arms are connected, and a spring connected to the said yoke.

9. A separator comprising, in combination, a frame, an oscillating tub mounted on said frame, 15 a cover for said tub extending over the upper edge of the said tub, means whereby material is supplied to said tub, a hollow dam centrally mounted of the said tub having an opening in the wall thereof through which the accepted material passes, a movable bottom comprising a closure member, extending beyond the edge of the said tub, a hollow member into which the said dam extends and a plate connected to said hollow member and in spaced relation with the said closure member, support assembly for said bottom consisting of units of turn-buckles, eye-bolts and springs connected together, one end of each unit being connected to the overhanging edge of the cover plate and the other to the bottom whereby the said bottom is normally held in spaced relation with the lower edge of said tub, arms extending alongside of the said tub having their lower ends extending between the said closure member and the spaced plate, rollers on said arms, a yoke to which the said arms are connected, and a spring connected to the said yoke.

10. A separator comprising, in combination, a frame, a ring mounted in said frame, a tub, rollers secured to said tub for engagement with the said ring, a cover for said tub extending over the upper edge of the said tub, means whereby material is supplied to said tub, a hollow dam centrally mounted of the said tub having an opening in the wall thereof through which the accepted material passes, a movable bottom into which the dam extends, support assembly for said bottom consisting of units of turn-buckles, eye-bolts and springs connected together, one end of each unit being connected to the overhanging edge of the cover plate and the other to the bottom whereby the said bottom is normally held in engagement with the said tub, and dumping means for the said tub comprising arms extending under one portion of the said bottom and secured to a movable yoke at their upper ends, and spring means tending to assist the support assembly in holding the movable bottom in engagement with the said tub.

11. A separator comprising, in combination, a frame, a tub mounted on said frame for oscillating movement, power means whereby the said tub is oscillated, a source of supply of material to be separated, a supply chute leading from said source of supply to said tub, a hollow dam centrally mounted of said tub having a discharge opening therein, a movable bottom for said tub, means on the tub whereby the movable bottom is normally held in spaced relation with the tub, means apart from the said tub whereby the bottom may be moved below the tub to allow for the escape of the reject material, the discharge opening in the dam being opposite the discharge end of the supply chute to the tub.

12. A separator comprising, in combination, a frame, a tub mounted on said frame for oscillating movement, power means whereby the said

tub is oscillated, a source of supply of material to be separated, a supply chute leading from said source of supply to said tub, a hollow dam centrally mounted of said tub having a discharge opening therein, a movable bottom for said tub, means on the tub whereby the movable bottom is normally held in spaced relation with the tub, and means apart from the said tub whereby the bottom may be moved below the tub to allow for the escape of the reject material, the discharge opening in the dam being spaced from the movable bottom and opposite the discharge end of the supply chute to the tub.

13. A separator comprising, in combination, a frame, a tub mounted for oscillating movement thereon, power means whereby the tub is oscillated, a cover for the said tub extending over the outer wall thereof, a movable bottom having an opening in the center thereof, suspension means for said bottom secured to the said cover plate, a hollow dam suspended centrally of the tub having a discharge opening in the side thereof and extending into the opening in the said bottom, a supply hopper, a power operated conveyor at the bottom of said hopper, a supply chute leading from said conveyor to the said tub having its discharge end opposite the discharge opening in the said dam, and manually operable means for moving the said bottom away from the said tub.

14. A separator comprising in combination, a frame, a tub mounted for oscillating movement thereon, power means whereby the tub is oscillated, a cover for the said tub extending over the outer wall thereof, a movable bottom having an opening in the center thereof, suspension means for said bottom secured to the said cover plate, a hollow dam suspended centrally of the tub having a discharge opening in the side thereof and extending into the opening in the said bottom, a supply hopper, power operated feed mechanism at the bottom of said hopper, a supply chute leading from said feed mechanism to the

said tub having its discharge end opposite the discharge opening in the said dam, and manually operable means for moving the said bottom away from the said tub.

5 15. A separator comprising in combination, a frame, a circular track mounted thereon, a tub mounted on said track for oscillatory movement, power actuated means connected to said tub whereby the said tub is oscillated, a cover for the said tub extending over the outer wall thereof, a movable bottom having an opening in the center thereof, suspension means for said bottom secured to the said cover plate, a hollow dam suspended centrally of the tub having a discharge opening in the side thereof and extending into the opening in the said bottom, a supply hopper, a power operated conveyor at the bottom of said hopper, a supply chute leading from said conveyor to the said tub having its discharge end opposite the discharge opening in the said dam, and manually operable means for moving the said bottom away from the said tub.

15 16. A separator comprising in combination, a frame, a circular track mounted on said frame, a tub, rollers secured to said tub for engagement with the said track, power actuated means connected to said tub whereby the said tub is oscillated, a cover for the said tub extending over the outer wall thereof, a movable bottom having an opening in the center thereof, suspension means for said bottom secured to the said cover plate, a hollow dam suspended centrally of the tub having a discharge opening in the side thereof and extending into the opening in the said bottom, a supply hopper, a power operated conveyor at the bottom of said hopper, a supply chute leading from said conveyor to the said tub having its discharge end opposite the discharge opening in the said dam, and manually operable means for moving the said bottom away from the said tub.

DICKINSON A. McNEIL, JR.
